(57) **CLAIM**

The ornamental design for a hose reel, as shown and described.

DESCRIPTION

FIG. 1 is an isometric view of a hose reel;

FIG. 2 is a front elevation view of the hose reel of FIG. 1;

FIG. 3 is a rear elevation view of the hose reel of FIG. 1;

FIG. 4 is a right side elevation view of the hose reel of FIG. 1;

FIG. 5 is a left side elevation view of the hose reel of FIG. 1;

FIG. 6 is a top plan view of the hose reel of FIG. 1; and FIG. 7 is a bottom plan view of the hose reel of FIG. 1; and, FIG. 8 is a rear perspective view of the hose reel of FIG. 1. The broken lines in the drawings are included for illustrating an environmental structure and form no part of the claimed design.
